TELEPHONE DIAL LOCK

Filed May 18, 1949

FIG. 1.

FIG. 2.

FIG. 3.

INVENTOR.

A. P. Gizzo
BY

Kimmel & Cornwall ATTORNEYS

I do not mean to confine myself to the exact details of construction herein disclosed, but claim all variations falling within the purview of the appended claims.

What I claim is:

1. A lock adapted to be removably mounted in the apertured wheel of a dial telephone comprising a housing having a coin slot, a headed stud fixedly carried by said housing and engageable in a selected wheel opening, a notched locking bolt rockably carried by said housing and cooperating with said stud in locking said housing to said wheel with said stud and bolt engaging in a selected opening of said wheel, said bolt including a cam shaped part projecting partly into said coin slot for rocking of said bolt to released position by an inserted coin, said slot being adapted to receive only a portion of the coin.

2. A lock adapted to be removably mounted in the apertured wheel of a dial telephone comprising a housing having a coin slot, a headed stud fixedly carried by said housing and engageable in a selected wheel opening, a notched locking bolt rockably carried by said housing and cooperating with said stud in locking said housing to said wheel with said stud and bolt engaging in a selected opening of said wheel, said bolt including a cam shaped part projecting partly into said coin slot for rocking of said bolt to released position by an inserted coin, and a key actuated lock bolt carried by said housing engageable with said projecting part for locking the latter against rocking by an inserted coin.

3. A lock adapted to be removably mounted in the apertured wheel of a dial telephone, comprising a housing having a coin slot and a passage

at one end of said slot communicating with the latter, a headed stud projecting from the bottom of said housing and formed with a slot aligning with said passage, said stud being engageable in a selected wheel opening, and a spring pressed notched locking bolt disposed in said passage and pivoted to said housing, the notched part of said bolt loosely engaging in the slot of said stud and said bolt including a cam shaped part confronting said first named slot engageable by a coin inserted in the latter whereby the inserted coin will rock said bolt to released position in the slot of said bolt, said slot being adapted to receive only a portion of the coin.

ALBERT P. GIZZO.
